FOLDABLE CAP

Frank K. Lipschutz, Louisville, Ky., assignor to Louisville Cap Corporation, Louisville, Ky., a corporation of Kentucky

Filed Apr. 27, 1959, Ser. No. 809,008
1 Claim. (Cl. 2—195)

This invention relates generally to caps, but has reference more particularly to caps of the type generally worn by the armed forces and known as "fatigue" caps, and to improvements in the cap disclosed in my U.S. Patent No. 2,896,218, issued July 28, 1959.

The present invention has as its primary object the provision of a cap of this type which is of simpler construction than the cap described in the aforesaid patent, and which can be manufactured in large quantities at lower cost than said cap.

Another object of the invention is to provide a cap of the character described which has greater appeal, in its external appearance, than caps heretofore used for this purpose.

Other objects and advantages of my invention will be apparent during the course of the following description.

In the accompanying drawings forming a part of this specification, and in which like numerals are employed to designate like parts throughout the same,

FIG. 1 is a top plan view of a cap embodying the invention;

FIG. 2 is a side elevational view of the cap;

FIG. 3 is a bottom plan view of the cap;

FIG. 4 is a top plan view of the cap, in folded or collapsed condition;

FIG. 5 is a side elevational view of the cap, in folded or collapsed condition;

FIG. 6 is a fragmentary cross-sectional view, taken on the line 6—6 of FIG. 1;

FIG. 7 is a fragmentary cross-sectional view, taken on the line 7—7 of FIG. 1;

FIG. 8 is a fragmentary cross-sectional view, taken on the line 8—8 of FIG. 7;

FIG. 9 is a fragmentary cross-sectional view, taken on the line 9—9 of FIG. 7;

FIG. 10 is a fragmentary cross-sectional view, taken on the line 10—10 of FIG. 2, and

FIG. 11 is a fragmentary cross-sectional view, taken on the line 11—11 of FIG. 2.

Referring more particularly to FIGS. 1, 2 and 3 of the drawings, which illustrate the cap in the open or unfolded condition in which it appears when worn, the cap will be seen to comprise a crown structure consisting of a front crown panel 1, a top crown panel 2 and rear crown panels 3, 4 and 5, these parts being made of a pliable textile or fabric.

The front crown panel is bent into substantially semi-cylindrical form, the axis of this cylinder being substantially vertical. This panel has a lower edge 1a which is curved to conform to the rear edge of a visor to be presently described, and has an upper edge 1b which is curved to conform with the front edge of the top panel 2. The lower edge of the panel 1 also includes portions 1c which extend rearwardly from the ends of the edge 1a and lie in a substantially horizontal plane.

The top panel 2 is curved or arched transversely to conform generally with the curvature of the edge 1b of the panel 1, and has a front edge which is rounded to conform with the upper edge 1b of the front crown panel 1, and a rear edge, which, in the flattened condition of the panel 2

2

is substantially straight, but which when the cap is worn, appears curved, as in FIGS. 1 and 2.

The rear crown panels 3, 4 and 5 are of substantially triangular shape, and of substantially the same size, the panel 4 being disposed between the panels 3 and 5.

As best shown in FIG. 6, the panel 1 is folded at its upper edge to provide a hem 6, which is secured, as by a line of stitching 7, to a downturned hem 8 at the front edge of the top panel 2. The raw edges of the hems 6 and 8 are bound or covered by a binding tape 9, which is secured to the hems 6 and 8 by means of the line of stitching 7.

Rearwardly of the hem 8, the front of the top panel 2 is folded downwardly, as at 10, and this downturned portion 10 is secured to the tape 9 and hems 6 and 8 by the line of stitching 7. This provides a fairly stiff upstanding rib at the meeting edges of the panels 1 and 2, as best shown in FIGS. 2 and 6, which, as will presently be explained, facilitates folding of the cap.

The tape 9 is also secured to the hems 6 and 8 by a second line of stitching 11, which is just below the stitching 7.

The rear edge of the top panel 2 is secured as by stitching 11a, to the front edges of the crown panels 3 and 5 (FIG. 7), these edges being covered by means of a binding tape 12 (FIGS. 1, 2, 3 and 7) which is secured to the panel 2 by a line of stitching 13, and to the panels 3 and 5 by a line of stitching 14, the tape covering the overlapped edges of the panels, as best shown in FIG. 7.

The rear edge of the panel 3 is secured, as by stitching 11b, to the adjacent edge of the panel 4 (FIG. 11), these edges being covered by means of a binding tape 15 (FIGS. 1, 2, 3, 4, and 11), which covers the overlapped edges of these panels, and which, as best shown in FIG. 11, is secured to the panel 3 by stitching 16, and to the panel 4 by stitching 17.

The other edge of the panel 4 is secured, as by stitching 11c to the rear edge of the panel 5 (FIG. 9), these edges being covered by means of a binding tape 18 (FIGS. 1, 2, 3, 4, 7 and 9), which covers the overlapped edges of these panels, and which, as best shown in FIG. 9, is secured to the panel 4 by stitching 19, and to the panel 5 by stitching 20.

The binding tapes 15 and 18, as best shown in FIGS. 1 and 3, are overlapped at their front ends, and these overlapped ends are inserted between the panels 3, 4 and 5 and the binding tape 12, being secured together at this point by the stitching 14.

The ends of the front crown panel 1 are provided with hems 21 (FIGS. 2 and 10), and the front edges of the rear crown panels 3 and 5 are provided with hems 22, the hems 21 and 22 being secured together by a line of stitching 23. The raw edges of these hems are bound or covered by the tape 12.

The cap also includes a visor of conventional crescent-shaped form, consisting of a flexible reinforcing insert or body 24 (FIG. 6), made of cork, plastic or like material, and coverings or facings 25 and 26 of the same textile or fabric as the crown portions of the cap. These coverings or facings 25 and 26 extend rearwardly beyond the rear edge of the body 24 to provide portions 27 and 28 respectively, which are secured as by stitching 29, to an upturned hem 30 of the panel 1.

A sweatband 31 is also provided, which is secured at its lower edge to the crown panels, as by stitching 32, the ends of this band being secured to each other at the rear of the cap, as by stitching 33, as best shown in FIGS. 7 and 8. The upper edge of this band is not stitched to the

crown structure, but may be tacked to the binding tapes 15 and 18 to hold it in place.

The crown structure further includes a reinforcing member or panel 35, which is coextensive in area with, and of the same contour or shape as the front crown panel 1. This member or panel 35 is preferably made of perforated plastic material, such as nylon, which is relatively stiff or rigid, as compared with the fabric or textile portions of the cap, but which is sufficiently flexible to be bent, yet has sufficient resiliency to cause it to return to its original shape or condition upon release of the forces or pressures which tend to bend it. This material, in other words, is a shape-retaining, resilient, semi-rigid or self-sustaining or supporting material which possesses all of these characteristics irrespective of the direction in which it is bent. The material, moreover, is preferably of an open or perforated structure so as to provide for maximum ventilation of the cap.

As best shown in FIG. 6, the reinforcing member 35 is provided at its upper edge with a downturned hem 36, which is sewn to the hems 6 and 8, and part 10 by the stitching 7, and is covered by the tape 9. It extends downwardly between the crown panel 1 and the hem 30, where it is secured to the panel 1 by stitching 37.

The ends of the reinforcing member 35 are, as best shown in FIG. 10, provided with hems 38, which are disposed between the panel 1 and the hems 21, and are secured to these parts by the stitching 13.

The cap, due to its construction, may be folded into a flat compact form, as shown in FIGS. 4 and 5, in which form it occupies a minimum of space, in both horizontal and vertical dimension, can be easily slipped into the pocket of the serviceman, remains unobtrusive while thus carried by the serviceman, and can be shipped or stored in large quantities, inexpensively, and with a minimum of labor or effort.

In folding the cap, the top crown panel 2 and the adjacent portions of the panels 3, 4 and 5 are pushed downwardly, and in doing this, the juncture of the panel 2 with the panels 3, 4 and 5 forms a natural fold line, which causes the portions of the panels 3, 4 and 5, to the left of a crease line A, as viewed in FIGS. 1, 2, 3 and 7, to be folded flat upon the panel 2. At the same time, the portions of the panels 3, 4 and 5 to the right of the crease line A, fold flat upon the other portions of these panels, the panel 2 folds flat upon the rear face of the panel 1, and the panel 1 folds flat upon the visor, creating a flat package, as shown in FIGS. 4 and 5.

This folding action is greatly facilitated by reason of the fact that the reinforcing member 35 provides a somewhat rigid panel, against which the portions of the cap rearwardly of this panel, and which are preferably left unlined, can be readily bent and folded flat. This folding is further facilitated by the provision of the upstanding rib 10, and the juncture of the panel 2 with the panels 3, 4 and 5, which juncture forms a natural fold line.

The portions of the cap rearwardly of the panel 1 are soft and flexible, and so shaped as to readily conform with the shape of the head, thereby providing a comfortable fit. In this connection, the triangular shape and arrangements of the panels 3, 4 and 5 is of importance, although it is to be understood that a greater or lesser number of these rear panels may be employed for this portion of the cap than the three which are illustrated.

The cap may be easily unfolded or opened to place it on the head of the wearer, by merely grasping the front edge of the visor with one hand and the rear edge of the panel 3 with the other hand and pulling these edges apart. When placed on the head of the wearer, the cap appears as shown in FIGS. 1 and 2, in which condition, the cap presents a neat, trim and attractive appearance.

It may be noted that when the cap is in the fully open position shown in FIG. 2, that the curve of the lower edge of the panel 1 extends upwardly, and is above the horizontal plane which passes through the lower edge of the

remaining portion of the crown of the cap, and that the rear edge of the visor of the cap, which is secured to the lower edge of the crown panel 1, is curved to conform with the curve of the lower edge of the crown panel 1.

5 This not only facilitates folding of the crown panel 1 flat on the visor when the cap is folded, but also enables the visor to be flipped upwardly to a vertical position and remain in such position, when the cap is worn, thereby permitting the visor to be above and out of the line of 10 vision for mechanics and others who are obliged to get into small spaces to work. This feature is applicable to caps which are of the folding or non-folding type.

It may also be noted that the lower edges of the panels 3, 4 and 5 lie in substantially the same horizontal plane 15 as the edges 1c of the crown panel 1, and that these edges, along with the edges 1c, lie in substantially the same horizontal plane as the lower edge of the visor. This aids in 20 creating a neat and attractive appearance for the cap, as a whole, when worn, and also aids in reducing the cap to a minimum-sized flat package, in the folded or collapsed condition of the cap.

25 It is to be understood that the form of my invention herewith shown and described, is to be taken as a preferred example of the same, and that various changes may be 30 made in the shape, size and arrangement of parts thereof, without departing from the spirit of the invention or the scope of the subjoined claim.

Having thus described my invention, I claim:

In a collapsible cap of the character described, a visor 35 having a concave inner edge, a crown structure comprising a front panel, a top panel and rear panels, said front panel bent into substantially semi-cylindrical form, the axis of said semi-cylindrical form being substantially vertical, said front panel having a curved upper edge and a lower edge, said lower edge having a portion thereof secured to the inner edge of the visor and end portions thereof extending rearwardly and lying in a common substantially horizontal plane, said top panel having a front and rear edge and being arched or curved transversely to 40 conform generally to the curvature of the upper edge of the front panel, said curved upper edge of the front panel being folded downwardly and rearwardly to provide a first hem, said front edge of the top panel being folded downwardly to provide a second hem generally parallel to and coextensive with the first hem, the front of the top panel rearwardly of the second hem being folded downwardly to provide a downturned portion generally parallel to and coextensive with said first and second hem, stitching means passing through and joining together said first hem, said second hem and said downturned portion, whereby said hems and downturned portion form a stiff upstanding rib at the juncture of the curved upper edge of the front panel with the front edge of the top panel, said rear panels being of substantially triangular shape, with their bases forming the base of the rear portion of the crown structure, said bases lying substantially in said horizontal plane, and their apices meeting at a point substantially at the center of the rear edge of the top panel, said rear edge of the top panel being connected to adjacent edges of at least two of said rear panels, 50 said front panel having a lining on its inner surface coextensive in area with, and of the same shape or contour as said front panel, said lining consisting of a perforated plastic material, which is relatively rigid as compared with the material of said front panel, but which is sufficiently flexible to be bent, yet has sufficient resiliency to cause it to return to its original shape or condition upon release of the forces or pressures which tend to bend it, 55 said top panel and rear panels being of a flexible, unlined, fabric, said cap being foldable along the concave inner edge of the visor, along the upper edge of the front panel, along the rear edge of the top panel, and along a curved line intermediate the rear edge of the top panel and the bases of said rear panels, to form a flat package, said stiff upstanding rib forming a natural fold line which facilitates 60 65 70 75

folding of the top panel onto the front panel during said folding.
